UNITED STATES PATENT OFFICE.

SYLVESTER S. HOWELL, OF CHICAGO, ILLINOIS.

MATERIAL SEPARATOR.

Application filed June 1, 1926. Serial No. 112,809.

This invention relates to a separator, and more particularly to a machine adapted to efficiently separate coke from furnace refuse or ash to reclaim the coke and segregate the clinkers, ash and other material in a compartment for convenient removal from the machine.

It is an object of this invention to provide a separating machine adapted to remove coke from furnace ash and the like.

It is also an object of this invention to provide a separator wherein a mixture of materials is deposited in the upper end of a material receiving unit whereby the lighter materials of the mixture are readily separated and drawn off, while the heavier materials are permitted to travel downwardly through the unit into a suitable receptacle for removal.

It is an important object of this invention to provide a material separating machine wherein a draft unit is provided with means for causing a shaft of liquid to rise therein against a deposited mixture of materials to cause the lighter materials to be readily separated and delivered from the unit while the heavier materials are permitted to travel downwardly through the shaft of water into a receiving compartment from which the heavier material may later on be withdrawn.

Other and further important objects of this invention will be apparent from the disclosures in the specification and the accompanying drawings.

This invention (in a preferred form) is illustrated in the drawings and hereinafter more fully described.

On the drawings:

Figure 1 is a top plan view of a separator embodying the principles of this invention showing a portion of the feed chute broken away.

Figure 2 is a vertical sectional view taken longitudinally of the machine on line II—II of Figure 1.

Figure 3 is a transverse vertical section taken on line III—III of Figure 1.

Figure 4 is an enlarged vertical detail section of the draft unit taken on line IV—IV of Figure 1.

Figure 5 is a detailed horizontal section taken on line V—V of Figure 4.

As shown on the drawings:

The reference numeral 1 indicates a floor or foundation having a pit or recess formed therein to receive a housing or casing 2 con-

structed of concrete or other suitable material, and having a transverse partition or wall 3 formed on the interior thereof and extending upwardly to approximately half 60 of the height of the housing 2. The housing 2 projects above the level of the floor 1 and is open at its upper end. Supported upon the upper edge of the partition 3 is an inclined barscreen or grate 4, which projects upwardly 65 to within a short distance of the upper edge of the housing 2. The partition 3 divides the interior of the housing 2 into a coke or light weight material receiving chamber 5, and into a clinker and ash or heavy weight 70 material receiving chamber 6.

Formed on the upper edge of two walls of the housing 2 are upwardly projecting arms or brackets 7, on which an I-beam 8 is supported diagonally above the housing. 75 Mounted upon the I-beam 8, and upon one wall of the housing 2, are a plurality of brace bars 9, which afford a framework for supporting a driving motor 10 in a vertical position. The motor 10 has connected thereto a vertical motor shaft 11, which projects downwardly through a suitable bearing 12 on the I-beam 8. Removably mounted on the lower end of the motor shaft 11 is a propeller 13 or other suitable means which 80 will cause an up draft of liquid, as herein-after more fully described.

The motor shaft 11 projects downwardly through a draft unit comprising a cylindrical intermediate section 14, an outwardly 90 flaring lower conical section 15, and an upwardly directed conical mouth piece or upper section 16. The draft unit is supported by means of bracket arms 17 and 18, the outer ends of which are secured to the 95 inner faces of certain of the casing walls, while the inner ends of the brackets are secured to flanged portions of a supporting ring 19, which is clamped around the intermediate cylindrical section 14 of the draft 100 unit. The upper end of the draft unit projects slightly above the upper edge of the housing 2 and has a segment thereof cut away to afford an outlet opening or discharge mouth 20, the lower edge of which is positioned above the upper level of the water 21 contained within the housing 2. Mounted above the housing 2, upon suitable supports (not shown), is an inclined channel 110 cross-sectioned material delivery chute 22, the lower end of which is positioned to project into the upper conical section 16 of the

draft unit to permit a material which is to be separated to be deposited directly into the upper end of the draft unit. Removably mounted on the inner surface of the intermediate cylindrical section 14 of the draft unit is a baffle plate or flange 23 provided for the purpose of retarding or breaking up the vortex of the column of water 24, which is caused to rise within the draft unit 10 when the machine is in operation.

The operation is as follows:

Before the machine is set into operation water is admitted into the housing 2 to fill both of the chambers 5 and 6 to a level 15 which is slightly below the upper edge of the housing. When the motor 10 is started the motor shaft 11 acts to rotate the propeller 13 thereby causing a column of water 24 to rise with a swirling motion upwardly 20 within the draft unit to a level higher than the level of the water within the housing 2. The action of the propeller in elevating the water tends to create a vortex at the upper end of the column of water. To retard the 25 vortex thus formed the baffle 23 is provided within the draft unit thereby affording a means for maintaining the level of the upper surface of the column of water 24 substantially level. While a propeller is illustrated and described as affording a means 30 whereby the column of water 24 may be caused to rise within the draft unit, it will, of course, be understood that any other suitable means may be provided to produce an upward draft of a liquid through the draft unit.

Furnace refuse or any other mixture of material which is to be separated is fed to the machine by way of the inclined delivery 40 chute 22, which directs the furnace refuse or material directly into the upper conical section 16 of the draft unit and into the upper end of the upwardly moving column of water 24. The draft unit acts as an up 45 draft tube wherein the ascending column of swirling water created by the propeller 13 acts on the deposited material to cause the lighter material, such as coke, to float or rise to the upper surface of the column 50 of water 24, while the heavier material such as ash, clinkers and the like is permitted to pass downwardly by the action of gravity through the draft unit and be deposited within the housing chamber 6.

55 The rising column of water 24 within the draft unit acts as a means for separating the materials of different weights so that the light weight material, such as coke, is retained in the upper portion of the draft unit, and is permitted to be flushed out of the upper section 16 through the discharge mouth or opening 20 and over the upper edge of the slightly inclined bar screen or 60 grate 4 to be deposited into the coke receiving chamber 5 of the housing 2, as clearly

illustrated in Figure 2 of the drawings. The bar screen 4 is provided for the purpose of permitting the water in the chamber 5 to return to the chamber 6. The screen 4 also prevents the separated coke from passing 70 into the chamber 6.

It will thus be seen that the material which is to be separated is deposited directly into the upper end of the draft unit on the lee side of the discharge mouth 20 in order 75

to allow time for the heavy particles to settle below the level of the water outlet before the rotating water carries it around to said outlet. The deposited material is thus carried into engagement with the rising column 80 of water 24, which is caused to rise within the draft unit by the propeller 13 or other suitable means to a level which is higher than the level of the water within the housing 2. The purpose of the top flare section 16 is to provide an increased liberating surface of water for the floats or light weight material. It furthermore facilitates feeding 85 of material into the upper end of the casing so that none of the heavy particles will be carried off with the floats. The top flare section also permits the use of a wider water outlet which is desirable, since the wider it is the less the depth of water over the outlet 90 weir need be to discharge the required amount of water to create the necessary velocity in the draft tube. The baffle 23 acts to retard the vortex of the column of water 24 thereby affording a substantially level 95 surface at the upper end of the column 24.

The light weight material, such as coke, therefore is not permitted to pass downwardly through the draft unit, but is held in suspension within the upper portion of the draft unit, and is carried upwardly by 100 the rising column of water so that the coke or light weight material is adapted to be carried off through the discharge opening 20 and delivered into the coke receiving chamber 5 from which it may be removed 105 by drag buckets or other suitable means. The clinkers, ash and other heavy material being acted upon by gravity are drawn downwardly through the draft unit and are deposited within the chamber 6 from which 110 they may be removed by any suitable means.

The purpose of providing the bottom flaring section 15 is to provide an enlarged enclosure for the propeller 13 to permit the same to deliver a quantity of water greater than that which actually passes up through the intermediate section 14 thereby allowing the surplus water to pass downwardly out of the lower flared section 15 carrying out 115 the heavy particles of the material through the space afforded between the ends of the propeller and the inner surface of the section 15 away from the rising column of water. Jamming of the descending heavy 120 particles between the tips of the propeller 125 130

blades and the interior wall of the draft unit casing is thus obviated by the use of the bottom flaring section. With the use of the bottom flare section there is an unusually large slip between the pitch travel of the propeller and the upward travel of water through the intermediate section, when the propeller is placed in the bottom flared section, thereby contributing to the successful elimination of the heavy particles of the material.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. A material separator comprising a housing, a draft unit positioned therein and comprising a cylindrical intermediate section, an outwardly flaring lower conical section secured thereto, an upwardly directed conical upper section secured on said intermediate section, said upper conical section having a discharge opening cut therein, a baffle plate secured on the inner surface of said cylindrical intermediate section, a driving means, a shaft connected therewith and projecting through the upper conical

section, the intermediate cylindrical section and into the lower conical section of said draft unit, and a propeller mounted on the lower end of said shaft within the lower draft unit section. 35

2. A material separating device, comprising a housing, a cylindrical sleeve mounted therein, means for supporting the same in position near the upper end of the housing, an outwardly flaring lower section secured to the lower end of said sleeve, an upwardly flaring upper section secured to the upper end of said sleeve, a baffle plate secured on the inner face of said sleeve, a propeller mounted to rotate in said lower flaring section and means for driving the propeller. 40 45

3. A material separating device, comprising a tubular member consisting of an intermediate sleeve, a lower flaring section and an upper flaring section having a discharge opening therein, a baffle member secured on the inner surface of said intermediate sleeve, a shaft projecting through the upper flaring section, the intermediate sleeve and into the lower flaring section, a propeller on said shaft within the lower flaring section, and means connected with said shaft to rotate the same. 50 55

In testimony whereof I have hereunto subscribed my name.

SYLVESTER S. HOWELL.
